DESIGN FOR A CORNER-PIECE FOR STORE-FRONT CONSTRUCTION

Application filed October 31, 1931. Serial No. 41,588. Term of patent 14 years.

To all whom it may concern:

Be it known that we, FRED HIMMEL and ISIDORE HIMMEL, citizens of the United States, residing at New Haven, in the county of New Haven and State of Connecticut, have invented a new, original, and ornamental Design for a Corner-Piece for Store-Front Construction, of which the following is a specification, reference being had to the accompanying drawings, forming part thereof.

Fig. 1 is a face view of a corner-piece for a store-front construction showing our new design;

Fig. 2 is a plan view of the same; and
Fig. 3 is an end view of the same.

We claim:

The ornamental design for a corner-piece for store-front construction as shown.

FRED HIMMEL.
ISIDORE HIMMEL.
